UNITED STATES PATENT OFFICE.

SWITS CONDÉ, OF OSWEGO, NEW YORK.

DESIGN FOR A KNIT FABRIC.

SPECIFICATION forming part of Design No. 14,046, dated July 10, 1883.

Application filed April 25, 1883. Term of patent 7 years.

To all whom it may concern:

Be it known that I, SWITS CONDÉ, of Oswego, in the county of Oswego, in the State of New York, have invented a new and useful Design 5 for Knit Fabrics, of which the following, taken in connection with the accompanying drawing, is a full, clear, and exact description.

This design consists in a peculiar form of stripes produced in knitted fabrics by the employment of different-colored yarns, and composed of two zigzag lines crossing each other at the center of their component consecutive bars, said stripes alternating with intervening parallel plain stripes, substantially as illustrated in the annexed drawing, wherein—

A denotes the figured stripes formed of the zigzag lines *a a*, crossing each other at the center of each consecutive bar, as aforesaid. These

figured stripes are arranged alternately with intervening parallel plain stripes, as shown. 20

What I claim is—

The design for knitted fabrics, consisting of figured stripes A, formed of zigzag lines *a a*, crossing each other at the center of their component consecutive bars, said figured stripes 25 alternating with intervening parallel plain stripes, substantially as described and shown.

In testimony whereof I have hereunto signed my name and affixed my seal, in the presence of two attesting witnesses, at Oswego, in the 30 county of Oswego, in the State of New York, this 3d day of April, 1883.

SWITS CONDÉ. [L. s.]

Witnesses:

EDW. MAXWELL,
JOSEPH J. REGAN.
